CLAIM

I claim the ornamental design for a mix and match card display set, as shown and described.

DESCRIPTION

FIG. 1 is an isometric view of a display with an example of celebratory type cards shown in dotted lines because the cards are not part of the claimed design but instead are used with the claimed design. The display is shown broken away to fit on drawing sheet.

FIG. 2 is a front view of the display. The display is shown broken away to fit on drawing sheet.

FIG. 3 is a back view of the display. The display is shown broken away to fit on drawing sheet.

FIG. 4 is a side view of the display. The display is shown broken away to fit on drawing sheet.

FIG. 5 is an enlarged bottom view of the vertical support and one of the display cards shown separately for clarity of illustration.

FIG. 6 is an enlarged top view of the vertical support and one of the display cards shown separately for clarity of illustration.

FIG. 7 is a front view of mix or match cut out shapes.

FIG. 8 is a front view of mix or match cut out shapes.

FIG. 9 is a front view of mix or match cut out shapes.

FIG. 10 is a front view of mix or match cut out shapes.

FIG. 12 is a front view of mix or match cut out shapes.

FIG. 13 is a front view of mix or match cut out shapes.

FIG. 14 is a front view of mix or match cut out shapes.

FIG. 15 is a front view of mix or match cut out shapes.

FIG. 16 is a front view of mix or match cut out shapes.
FIG. 17 is a front view of mix or match cut out shapes.
FIG. 18 is a front view of mix or match cut out shapes.
FIG. 19 is a front view of mix or match cut out shapes.
FIG. 20 is a front view of mix or match cut out shapes.
FIG. 21 is a front view of mix or match cut out shapes.
FIG. 22 is a front view of mix or match cut out shapes.
FIG. 23 is a front view of mix or match cut out shapes.
FIG. 24 is a front view of mix or match cut out shapes.
FIG. 25 is a front view of mix or match cut out shapes.
FIG. 26 is a front view of mix or match cut out shapes.
FIG. 27 is a front view of mix or match cut out shapes.
FIG. 28 is a front view of mix or match cut out shapes.
FIG. 29 is a front view of mix or match cut out shapes.
FIG. 30 is a front view of mix or match cut out shapes.
FIG. 31 is a front view of mix or match cut out shapes.

FIG. 32 is a front view of mix or match cut out shapes.
FIG. 33 is a front view of mix or match cut out shapes.
FIG. 34 is a front view of mix or match cut out shapes.
FIG. 35 is a front view of mix or match cut out shapes.
FIG. 36 is a front view of mix or match cut out shapes.
FIG. 37 is a front view of mix or match cut out shapes.
FIG. 38 is a front view of mix or match cut out shapes.
FIG. 39 is a front view of mix or match cut out shapes.
FIG. 40 is a front view of mix or match cut out shapes.
FIG. 41 is a front view of mix or match cut out shapes.
FIG. 42 is a front view of mix or match cut out shapes.
FIG. 43 is a front view of matched cut out shapes and a reduced-size, comprehensive view; and,
FIG. 44 is a front view of mixed cut out shapes and a reduced-size, comprehensive view.
